VERTICALLY ADJUSTABLE WORK HOLDER
AND SUPPORT THEREFOR, INCLUDING
MOTOR MOUNTAlbert Von Gunten, Eudora, Kans., assignor to
Eudora Beltless Specialty Machine Co., Inc.,
Eudora, Kans., a corporation of Kansas

Application July 6, 1948, Serial No. 37,209

1 Claim. (Cl. 144—134)

1

This invention relates to improvements in wood shapers and is directed to improvements in the efficiency in operation thereof.

A primary object of the invention is to provide novel means for mounting the cutter in order to eliminate any possible displacement thereof and to insure direct action by the motor at all times.

Another important object of the invention is to provide means to retain the cutter element directly on the drive means itself and thus avoid the inconvenience and expense of separately operating connections generally in use today with the accompanying loss in motion when the operation of the device is begun, as well as the additional elements used being subject to mechanical failure and replacement.

And another important object of the invention is to eliminate the usual type of end thrust provided for motors in use today and by the use of a rotatable ball upon which the motor spindle rests, attaining the identical result obtained in the usual and more expensive motors now available.

Still another object of the invention is to provide means for adjusting the height of the work table by simple rotative movement of a hand wheel in connection with the said work table.

With these features in view, the invention consists of certain features of novelty in the construction, combination and arrangement of parts by which said features and certain others, hereinafter appearing, are effected—all as fully described with reference to the accompanying drawings and more particularly pointed out in the appended claim.

In the drawings:

Figure 1 is a side elevation of the invention with the cutter mounted directly on the motor spindle;

Figure 2 is a front elevation of the shaper of the invention, but disclosing a modified means for mounting the cutter head thereon;

Figure 3 is a horizontal view taken on the broken lines 3—3 in Figure 1;

Figure 4 is a rear end view of the shaper of the invention with certain parts being shown in section;

Figure 5 is an exploded perspective view of the cutter and means for retaining the same of the embodiment shown in Figure 2;

Figure 6 is an enlarged vertical sectional view of the adjusting means;

Figure 7 is an enlarged view of the cutter and

2

the mounting means therefor illustrated in Figure 1; and

Figure 8 is an end view of the cutter element.

Referring to the figures, the wood shaper of the invention is indicated generally at 10 and includes a base 12 upon which an adjustable table support 14 is secured on a base plate 16 retained on base 12 by suitable means such as bolts 18. A work table 20 is adjustably retained in position by a support plate 22 secured thereto by retaining bolts 24 or the like. A cutter 26 is mounted and retained above table 20 in operative position, as will soon be described.

Motor 28 is retained on an upwardly tapering support 30 suitably mounted on base 12 and is connected by wires 32 to an actuating switch 34 and a source of current supply, not shown, in the usual manner, this forming no part of the invention. Motor 28 includes the usual motor spindle 36 extending axially therethrough and retained in an upper bearing or bushing 38 secured in adjustable support means 14 at the upper end thereof and in a similar bushing 40 retained in a counterbored portion 44 of motor support 30. It is to be noted at this point that the lower end of spindle 36 does not contain the usual end thrust bearing provided in motors in use today, but instead terminates in a straight shaft that extends into a bearing 30a within a recess 40 in the support 30 and seats upon a spindle ball 46 retained on the base of counterbore 44 and within the bearing 30a to rotate thereon. Thus, it is readily apparent that a simplified type of motor has been provided and one which attains the identical results of other motors now in use with the elimination of cost in the manufacture thereof. The upper portion of spindle 36 extending beyond motor 28 includes a sleeve 48, spindle 36, and sleeve 48 extending through suitable apertures 50 and 52 in support plate 22 and work table 20, respectively. Sleeve 48 terminates a short distance below the upper extremity of spindle 36 and forms an annular seating shoulder 54. Spindle 36 terminates in a threaded section 56 where it projects beyond sleeve 48 in order to receive cutter heads 26 and locking means therefor thereon.

Referring to Figures 1 and 7, one form of cutter 26 is illustrated and includes an apertured annular ring 58 rotatably retained on spindle end 56 and seating on shoulder 54 of sleeve 48. Ring 58 includes a pair of oppositely disposed cutters 60 including cutting edges 62 in a manner well known in the art. A cutter locking or retaining means 64 is axially bored throughout the length

thereof and is rotatably received on spindle end 56 to seat on the upper extremity of ring 58 and thereby press it into non-movable position on shoulder 54 of sleeve 48, lock 64 being secured to spindle 36 by suitable set screw means 66. A modification in the construction of the spindle and cutter is illustrated in Figures 2 and 5, spindle 36 including a transverse slot 68 and cutter 26 containing a depending transverse flange 70 on the lower extremity thereof to seat in keyway 58, thereby insuring additionally the non-slip relation thereof. Cutter lock 72 is similar in construction to lock 64, but different therefrom in that the axial bore therein terminates in the head portion thereof and does not extend entirely therethrough. Set screw 66 serves to retain lock 72 on spindle head 56.

The adjustable support 14 includes a depending, transverse frame 74 secured integrally with the lower portion of plate 22 and containing depending legs 76, legs 76 including lateral apertured guide or slideway sleeves 78 and a medial, laterally and downwardly bar 80 extending therefrom. Lateral braces 82 are provided for support member 14, as is clearly seen in Figure 1. Guide sleeves 78 receive therethrough vertically extending support rods 90 suitably journaled at 86 at the lower extremity thereof, their journals 86 being welded or otherwise mounted on base plate 16. Bearings 88 engage the upper extremities of support rods 90 and serve as a stop means for the vertical adjustment of table support 22, bearings 88 being held in operative position by means of vertical support members 14 mounted on base plate 16. The bar 80 terminates in a lateral apertured bearing 92, threaded internally to receive therein a threaded rod 94 mounted in counterbore 96 (Figure 6) and suitably welded thereto at 98 in hand wheel 100. Hand wheel 100 includes a lower, axially counterbored base 102, bore 104 retaining a vertical stud or key 106 extending from base plate 16 and thereby retaining wheel 100 in operative position. Thus, by rotating hand wheel 100, threaded rod 94 rotates to vertically adjust support plate 22, and as a consequence work table 20, this being possible by the engagement of slideway sleeves 78 with support rods 90. Bearings 88 stop the vertical movement of support 74 to prevent disengagement thereof from the retaining means. Motor 28 is also retained in position by a cross member 90' whose ends receive bolts 108 that are threaded in apertures the rear of support 14.

In use, the desired cutter head 26 is seated on the extending extremity 56 of spindle 36 and is retained thereon by suitable locks 64 or 72. Since spindle 36 extends through motor 28 and retains cutter head 26 thereon, the necessity for providing auxiliary equipment such as pulley and

belt connections is eliminated and cutter 26 is directly driven from motor 28. Spindle 36 rotates freely on ball 46 and thereby eliminates the necessity for supplying end thrust bearings normally employed. When it is desired to adjust table 20, hand wheel 100 is rotated, thereby moving support 74 in a vertical direction until the desired height has been attained.

It is to be understood that the invention above described is not limited to the exact arrangement and combination of parts as described in the specification, nor is the invention limited to the exact details of construction as illustrated in the accompanying drawings.

Having described the invention, what is claimed as new is:

A wood shaper comprising a base, a pair of uprights rising from the base and having upper and lower lateral projections, each of said projections having a vertical bore therein with the bores in the upper projections being in registry with the bores in the lower projections, a pair of guide bars extending through the bores in said projections and paralleling said uprights, a horizontal table, a substantially U-shaped frame depending from the table and including a pair of vertical legs, vertical guide sleeves carried by said legs and slidable on said bars between said upper and lower projections, a horizontal cross-member mounted on and extending between said uprights, a motor supported on said base and also supported by said cross-member, said motor including a vertical drive shaft, said table having an opening receiving said shaft, a vertical stud rising from the base, a hand wheel having a hub, said hub having a recess receiving said stud, an arm inclining downwardly from the frame and having a horizontal extension at its lower end overlying the hand wheel, said extension having a threaded aperture therein, and a threaded rod fixed to said wheel and threaded in said aperture.

ALBERT VON GUNTEN.
